UNITED STATES PATENT OFFICE.

DOUGLAS TURNER AND ROBERT C. GRIER, OF ST. LOUIS, MISSOURI.

UNIVERSAL DRAWING MACHINE.

1,414,002.

Specification of Letters Patent. Patented Apr. 25, 1922.

Application filed March 9, 1921. Serial No. 450,991.

To all whom it may concern:

Be it known that we, DOUGLAS TURNER and ROBERT C. GRIER, citizens of the United States, residing in the city of St. Louis and 5 State of Missouri, have invented new and useful Improvements in Universal Drawing Machines, of which the following is a specification.

This invention relates to a universal drawing machine or instrument such as used by draftsmen in preparing drawings. The general object of the invention is to produce an instrument of this type, which is very simple in construction and which can 10 be used with facility. The instrument about to be described is of the type which embodies in its construction a slide which is movable along a blade such as the blade of a T-square. The invention concerns itself especially with the construction of this slide and a special object of the invention is to construct the slide in such a way as to enable it to co-operate with T-square blades of different thicknesses or widths. The invention 15 also concerns the details of construction of the slide as regards the attachment of a radial arm carrying a detachable ruling arm or scale to co-operate with a fixed protractor carried by the scale.

Further objects of the invention will appear hereinafter.

The invention consists in the novel features, and in the general combination of parts to be particularly described herein-after, all of which contribute to produce a simple and efficient universal drawing machine. A preferred embodiment of our invention will be particularly described in the following specification, while the broad 20 scope of our invention will be pointed out in the appended claims.

In the drawing—

Figure 1 is a plan of a universal drawing machine or instrument embodying our invention;

Figure 2 is a section taken through the edge of the blade and illustrating a guide bracket which may be employed to assist in guiding the blade when the same is being 25 moved up or down on the face of the drawing board;

Figure 3 is a plan of the slide upon an enlarged scale, and showing a short portion of the blade;

Figure 4 is a view showing the slide and 55 its attached parts in end elevation but showing the protractor and blade in cross-section;

Figure 5 is a vertical section taken through the geometric center of the protractor, upon 60 an enlarged scale;

Figure 6 is a plan showing the inner end of a ruling arm and particularly illustrating the features of its construction which facilitate its being detachably secured to the 65 center of the protractor;

Figure 7 is a double view showing a fastening means or screw in plan and in side elevation; this screw may be employed for securing the ruling arm to the center 70 pin of the slide.

In the drawing 1 represents a drawing board of any suitable type upon which a blade 2 rests, and is movable up and down. This blade may be the blade of an ordinary 75 T-square, but any other suitable means may be provided for enabling the blade to maintain itself parallel to a horizontal line on the board. In the present instance we have illustrated the blade as being connected at 80 each end to an equalizer cord 3, the runs of which pass around guide pulleys 4, 5, and 6 placed at the corners of the board. In order to prevent the blade from shifting longitudinally and assist in guiding it on 85 the board, we provide each end of the blade with a small clamp 7 the side of which engages the end edge 8 of the board. Our invention concerns the construction of the slide 9. This slide is constructed so that it 90 presents a channel 10 on its under side and this channel has a depth which is slightly greater than the greatest thickness of the blade 2, that the slide is expected to be mounted upon. In addition to this the slide 95 is provided with means for clamping the upper and lower edges. The slide preferably comprises a translucent plate 11 of celluloid or similar material which extends across the upper face of the blade adjacent the upper edge 12 of the blade, and under the upper portion of the plate 11 a bracket 13 of fiber or similar material is attached. This bracket is provided with a longitudinally disposed groove 14 formed in a plane 100

parallel with the plane in which the blade 2 lies. The plate 11 and the bracket 12 project beyond the upper edge 12 of the blade 105

to carry a protractor 15 and a sweep-arm 16. The protractor 15 has a degree scale 17 at its outer edge and has a central opening 18. The protractor also includes a cross bar 5 or chord-bar 19 which is received in the groove 14 and secured therein in any suitable manner as by means of rivets 20. The bracket 13 presents a vertical face 21 which operates as a straight edge to come in contact with the upper edge 12 of the blade 2. In order to adjust the width of the channel 10 to the blade we provide an elongated shoe 22 having a vertical face or edge 23 to engage the lower edge 24 of the blade 15 and this shoe is provided with a clamping nut 25 mounted upon a threaded stem which extends up from the shoe 22 and passes through a slot 26 disposed in the part of the upper plate 11 which extends below the lower edge of the blade. However, any suitable means may be provided for adjusting the shoe toward or from the blade or for holding the shoe against the edge 24. The shoe merely enables the slide to be properly guided along the blade. A ruling arm 27 is provided which is mounted to swing on an axis coinciding with the geometric center of the protractor. This ruling arm is provided with a straight edge 30 28 to be used by the draftsman for guiding his pencil in the same manner as a triangle. As drawings are frequently made on different scales it is advisable to have this ruling arm detachable. For this reason we prefer to construct the inner end of the ruling arm in such a way as to facilitate its being detachably secured to the sweep-arm 16. We also provide means for frictionally clamping the ruling arm so that it will stay in any position in which it is left. In order to accomplish this we prefer to provide a center pin or stud 29 which is received loosely in a bushing 30, and this bushing is seated on the upper face of the plate 11 (see Fig. 4). The upper end of the center pin 29 is formed into a threaded stem 31 of reduced diameter so that an annular shoulder 32 is formed just above the bushing. The lower portion of the stud passes through the plate 11 and through the upper or thin portion 33 of the bracket or block 13. The sweep-arm 16 has an opening at its inner end which receives a reduced neck 34 formed on the lower portion of the stud; in this way an annular shoulder 35 is formed against which the sweep-arm seats. The sweep-arm and the ruling arm 27 have co-operating interlocking means to enable the arm to be secured to the sweep, and means is provided for attaching the inner end of the ruling arm 27 to the lower end of the center pin or stud 29. For this purpose the under side of the sweep-arm 16 is provided with a dowel 36 and the arm 27 is provided with an opening 37 to receive

the dowel. The ruling arm 27 is also provided with a central opening 38 through which passes the threaded stem 39 of a small screw which is screwed into the lower end of the center pin. This screw may be provided with a flat head 40 having spanner notches 41 in its edge and this head is countersunk into a recess 42 in the under face of the ruling arm 27. It should be understood that the diameter of the threaded stem 39 fits neatly into the opening 38 so that this screw and the dowel 36 accurately determine the position of the ruling arm. In order to frictionally and yieldingly clamp the parts together we provide a spring washer 43 which is disposed under the lower face of a knob 44 which screws onto the stem 31. The lower face of this knob 44 is jammed tight against the shoulder 32 so that the sweep-arm 16 and the ruling arm 27 carried thereby are frictionally held between the head 40 and the bushing 30. The ruling arm 27 is provided with vernier lines 45 adjacent to the edge of the protractor and the line 46 which carries an arrow and co-operates with the lines of the protractor scale 17 to indicate the relation of the ruling edge 28 with respect to horizontal and vertical lines on the face of the board. In the position shown, this ruling arm is in the 30° position, that is to say, the edge 28 forms an angle of 30° with the edge 12. We provide means for indicating when the ruling arm is in any one of the positions in which it is usually left, for example, 30°, 45°, 60° and 90°. For this purpose we provide the inner edge 47 of the protractor with means to co-operate with other means on the sweep-arm 16. In the present instance we provide a plurality of notches 48 on the edge 47, any individual of which may co-operate with a small leaf spring 49 which is mounted in a pin 50 on the upper side of the sweep-arm.

With a universal drawing machine or instrument having the features of this invention it will be evident that ruling arms such as the ruling arm 27 of different scales may be readily substituted for each other, and in using the instrument the ruling arm 110 may be readily moved and automatically held in any desired position forming an angle with the blade. The ruling arm may be moved on its axis by taking hold of the ruling arm near its outer end or if desired 115 it may be rotated by seizing the knob 44. A drawing instrument having these features evidently may be constructed at a very low cost and evidently also can be used with great facility by a draftsman in making 120 working drawings to scale.

It is understood that the embodiment of the invention described herein is only one of the many embodiments our invention may take, and we do not wish to be limited in 125 130

the practice of our invention nor in our claims, to the particular embodiment set forth.

What we claim is:—

5. 1. In a universal drawing machine, the combination of a drawing board, a transverse blade resting on the board and movable up and down upon the board, means associated with the blade for maintaining the same parallel to a horizontal line drawn on the board, a slide resting upon the board and movable along the blade, said slide having a channel on its under side of greater depth than the thickness of the blade and receiving the blade, means for clamping the slide against the upper and lower edges of the blade, a protractor fixed to the slide, having a scale, a sweep-arm having a pivotal axis at the geometric center of the protractor, and a ruling arm detachably secured to said sweep-arm, extending substantially radially from the center of the protractor and projecting across the board beyond the protractor. 70
10. 2. In a universal drawing machine, the combination of a drawing board, a transverse blade resting on the board and movable up and down upon the board, means associated with the blade for maintaining the same parallel to a horizontal line drawn upon the board, a slide resting upon the board, movable along the blade, and having a channel on its under side receiving the blade, means for clamping the slide against the edges of the blade, said slide having a longitudinal groove in the upper edge thereof, a protractor having its lower edge received in said groove and secured therein, a ruling arm pivotally mounted on the geometrical axis of the protractor, lying upon the face of the board beyond the protractor, and carrying a scale, and means for frictionally clamping the ruling arm to enable the same to maintain itself in any position in which it is left. 75
15. 3. A universal drawing machine constructed as set forth in claim 2, in combination with a knob on the pivotal axis at the geometric center of the protractor by means of which the ruling arm may be swung around the axis. 80
20. 4. A universal drawing machine constructed as set forth in claim 2, in combination with co-operating means respectively on the arm and the protractor, for indicating when the ruling arm is disposed at a predetermined angle. 85
25. 5. In a universal drawing machine, the combination of a drawing board, a transverse blade resting on the board and movable up and down upon the board, means associated with the blade for maintaining the same parallel to a horizontal line drawn upon the board, a slide resting upon the board, movable along the blade, and having a channel on its under side receiving the blade, means for clamping the slide against the edges of the blade, a protractor fixed to the slide in a position to extend over the board beyond the upper edge of the blade, a center pin mounted in the slide on the geometrical axis of the protractor, a sweep-arm on the pin having a dowel on its under side, a scale arm resting upon the face of the board having an opening receiving the dowel and having an opening to receive the lower end of said center pin, and means for securing the said ruling arm to the center pin. 90
30. 6. In a universal drawing machine, the combination of a drawing board, a transverse blade resting on the board and movable up and down upon the board, means associated with the blade for maintaining the same parallel to a horizontal line drawn upon the board, a slide resting upon the board, movable along the blade, and having a channel on its under side receiving the blade, means for clamping the slide against the edges of the blade, a protractor fixed to the slide in a position to extend over the board beyond the upper edge of the blade, a center pin mounted in the slide on the geometrical axis of the protractor, a sweep-arm on the pin having a dowel on its under side, a scale arm resting upon the face of the board having an opening receiving the dowel and having an opening to receive the lower end of said center pin, and means for securing the said ruling arm to the center pin. 95
35. 7. In a universal drawing machine, the combination of a drawing board, a transverse blade resting on the board and movable up and down upon the board, means associated with the blade for maintaining the same parallel to a horizontal line drawn upon the board, a slide resting upon the board, movable along the blade, and having a channel on its under side receiving the blade, means for clamping the slide against the edges of the blade, a protractor fixed to the slide in a position to extend over the board beyond the upper edge of the blade, a center pin mounted in the slide on the geometrical axis of the protractor, a sweep-arm on the pin having a dowel on its under side, a scale arm resting upon the face of the board having an opening receiving the dowel and having an opening to receive the lower end of said center pin, and means for securing the said ruling arm to the center pin. 100
40. 8. In a universal drawing machine, the combination of a drawing board, a transverse blade resting on the board and movable up and down upon the board, means associated with the blade for maintaining the same parallel to a horizontal line drawn upon the board, a slide resting upon the board, movable along the blade, and having a channel on its under side receiving the blade, means for clamping the slide against the edges of the blade, a protractor fixed to the slide in a position to extend over the board beyond the upper edge of the blade, a center pin mounted in the slide on the geometrical axis of the protractor, a sweep-arm on the pin having a dowel on its under side, a scale arm resting upon the face of the board having an opening receiving the dowel and having an opening to receive the lower end of said center pin, and means for securing the said ruling arm to the center pin. 105
45. 9. In a universal drawing machine, the combination of a drawing board, a transverse blade resting on the board and movable up and down upon the board, means associated with the blade for maintaining the same parallel to a horizontal line drawn upon the board, a slide resting upon the board, movable along the blade, and having a channel on its under side receiving the blade, means for clamping the slide against the edges of the blade, a protractor fixed to the slide in a position to extend over the board beyond the upper edge of the blade, a center pin mounted in the slide on the geometrical axis of the protractor, a sweep-arm on the pin having a dowel on its under side, a scale arm resting upon the face of the board having an opening receiving the dowel and having an opening to receive the lower end of said center pin, and means for securing the said ruling arm to the center pin. 110
50. 10. In a universal drawing machine, the combination of a drawing board, a transverse blade resting on the board and movable up and down upon the board, means associated with the blade for maintaining the same parallel to a horizontal line drawn upon the board, a slide resting upon the board, movable along the blade, and having a channel on its under side receiving the blade, means for clamping the slide against the edges of the blade, a protractor fixed to the slide in a position to extend over the board beyond the upper edge of the blade, a center pin mounted in the slide on the geometrical axis of the protractor, a sweep-arm on the pin having a dowel on its under side, a scale arm resting upon the face of the board having an opening receiving the dowel and having an opening to receive the lower end of said center pin, and means for securing the said ruling arm to the center pin. 115
55. 11. In a universal drawing machine, the combination of a drawing board, a transverse blade resting on the board and movable up and down upon the board, means associated with the blade for maintaining the same parallel to a horizontal line drawn upon the board, a slide resting upon the board, movable along the blade, and having a channel on its under side receiving the blade, means for clamping the slide against the edges of the blade, a protractor fixed to the slide in a position to extend over the board beyond the upper edge of the blade, a center pin mounted in the slide on the geometrical axis of the protractor, a sweep-arm on the pin having a dowel on its under side, a scale arm resting upon the face of the board having an opening receiving the dowel and having an opening to receive the lower end of said center pin, and means for securing the said ruling arm to the center pin. 120
60. 12. In a universal drawing machine, the combination of a drawing board, a transverse blade resting on the board and movable up and down upon the board, means associated with the blade for maintaining the same parallel to a horizontal line drawn upon the board, a slide resting upon the board, movable along the blade, and having a channel on its under side receiving the blade, means for clamping the slide against the edges of the blade, a protractor fixed to the slide in a position to extend over the board beyond the upper edge of the blade, a center pin mounted in the slide on the geometrical axis of the protractor, a sweep-arm on the pin having a dowel on its under side, a scale arm resting upon the face of the board having an opening receiving the dowel and having an opening to receive the lower end of said center pin, and means for securing the said ruling arm to the center pin. 125

In testimony whereof, we have hereunto set our hands.

DOUGLAS TURNER.
ROBERT C. GRIER.
